US00D861608S

(12) **United States Design Patent** (10) **Patent No.:** **US D861,608 S**
(45) **Date of Patent:** **** Oct. 1, 2019**

(54) **CONTROLLER FOR SERVOMOTORS**

(71) Applicant: **Mitsubishi Electric Corporation**,
Tokyo (JP)

(72) Inventors: **Shinichi Kato**, Tokyo (JP); **Asuna
Osawa**, Tokyo (JP); **Masaaki
Kadoyanagi**, Tokyo (JP); **Shotaro
Hirako**, Tokyo (JP)

(73) Assignee: **Mitsubishi Electric Corporation**,
Tokyo (JP)

(**) Term: **15 Years**

(21) Appl. No.: **29/642,621**

(22) Filed: **Mar. 30, 2018**
